UNITED STATES PATENT OFFICE

ERNEST F. KAHLERT AND EMIL CARLSON, OF BROWERVILLE, MINNESOTA

CHIMNEY SWEEPER

Application filed March 18, 1930. Serial No. 436,804.

This invention relates to improvements in chimney sweepers.

An object of the invention is to provide a chimney sweeper having adjustable cleaning elements associated therewith and being arranged whereby the effective area of the cleaning elements may be varied while the sweeper is in operation.

Another object is to provide a device of the character referred to wherein means are provided for varying the effective area of the cleaning elements and for operating said means from a point outside the chimney.

A further object is to provide novel means for varying the effective area of the cleaning elements.

Other objects and advantages of the invention will become apparent during the course of the following description.

In the drawing we have shown preferred embodiments of the invention. In this showing,

Figure 1 is a front elevation of one form of the device,

Figure 2 is a plan view thereof,

Figure 3 is a front elevation of a modified form of the device,

Figure 4 is a plan view of the modified form, and,

Figure 5 is a side elevation of the latter form.

Referring to the drawing the numeral 10 indicates the body or frame of the sweeper as a whole, formed of a plurality of elliptically shaped resilient members 11 arranged in spaced relation with respect to each other and further arranged with contacting portions adjacent the upper and lower ends of the body. These contacting portions may be secured together or the resiliency of the members 11 may be utilized to retain the contact between these portions.

A rotatable member 12 provided with a threaded portion 13' adjacent its lower extremity extends through suitable openings in the contacting portions of the resilient members as indicated in Figure 1. Adjacent the upper contacting portions of the resilient members, collars 13 and 14 are secured to the member 12 on opposite sides of the con-

tacting portions. The arrangement of the collars is such that longitudinal movement on the member 12 of the upper ends of the resilient members is prevented, while rotation of the member 12 is freely permitted. The openings in the lower end of the resilient members are threaded to receive the threaded portion 13' of the rotatable member and a nut 15 is threaded on the member 12 outwardly of the resilient members. From the construction described it will be obvious that rotation of the member 12 will cause the lower extremities of the resilient members to move longitudinally of the member 12 while the upper extremities remain in fixed position, thus permitting changes in the shape of the resilient members.

A cleaning element, preferably in the form of a wire brush 16, is welded or otherwise suitably secured on each side of each elliptical member by means of a brace or arm 17. As shown in Figure 2 each brush 16 is substantially of right angle shape, the brushes of one resilient member being arranged in a different horizontal plane than the brushes of the other member. The arrangement of the brushes is such that a substantially square cleaning unit is formed.

Referring to Figures 3, 4 and 5, a modified form of the invention is shown in which only one of the resilient members 11 is used. The rotatable member 12 extends through opposite ends of this member in the same manner as previously described in connection with Figures 1 and 2 whereby the resilient member may be changed in shape by rotation of the member 12.

In this form of the invention a substantially T-shaped plate 18 is arranged on each side of the resilient member and is spaced therefrom by means of a U-shaped spacing member 19, both members, 18 and 19, being secured in place by rivets 20 or the like. Each T-shaped member is provided with a longitudinal slot 21 in the shank portion thereof and is also provided with longitudinal slots 22 in the opposite arms thereof.

In this form of the invention each cleaning element is formed in two sections 23 hingedly connected together by the hinge 24.

The pivot pin 25 of the hinge has its inner end extended whereby the pin is slidable in the slot 21, the head 25' of said pin being wider than the slot and being adapted to snugly engage the arms of the U-shaped member 19 whereby the pin will be guided in its movements in the slot 21 and will be retained therein. The outer end of the pin 25 is also extended and threaded to receive a wing nut 26 which may be utilized to secure the pin in selected positions in the slot 21. Each section 23 of the cleaning elements has a pin 27 suitably carried thereby, one end of which slides in the adjacent slot 22 during movement of the pin 25 in the slot 21.

In both forms of the invention the rotatable member 12 is provided with an opening 28 adjacent its upper end and the latter is formed with an eye 29. An extension rod 30 is provided with an offset portion 31 extending through the eye 29 as indicated in Figure 5 and its lower extremity is provided with an opening 32 adapted to align with the opening 28. A bolt 33 is threaded through the openings 28 and 32 to tighten the extension rod and the member 12 together and it will be obvious that a rigid connection is formed between the rod and the extension member. As indicated in Figure 5 any number of these extension rods may be utilized, depending upon the height of the chimney to be cleaned.

The operation of the device is as follows:

The form of the invention shown in Figures 1 and 2 is adapted for use in cleaning square chimneys. In many instances it has been found that chimneys often vary in width between their upper and lower ends and it is not uncommon to find chimneys of sixteen inch width at their bottom which taper to a width of only eight inches at their top. With the device shown in Figures 1 and 2 the rod 12 may be rotated until the square formation of the cleaning elements 16 will snugly fit the bottom of the chimney. As many of the extension rods 30 as may be necessary to reach above the top of the chimney are then connected to the rod 12, so that the device may be pulled upwardly by a man standing at the top of the chimney. As the device is pulled upwardly by the operator any decrease in size of the chimney may be compensated for by rotation of the member 12 through the extension rods, so that the square formation of the cleaning elements is reduced in size and such change in the size of the square formation may be continued until the device reaches the top of the chimney. If it is desired to clean downwardly the operation of the device would be the reverse to that described. The nut 15 is arranged at a suitable position on the threaded portion of the member 12 and limits the downward movement of the resilient members when the

effective area of the cleaning elements is to be changed.

In the form of invention shown in Figures 3, 4 and 5 the operation of member 12 to change the shape of the resilient member 11 is the same as that previously described and may be regulated from the top of the chimney. This form of the invention is adapted for cleaning two walls of a square chimney at a time, although it will be obvious that a circular chimney may also be cleaned if curved cleaning elements are used. In this form of the invention the means for varying the effective area of the cleaning elements must be set manually before the device is placed for operation in a chimney as it is difficult to change the effective area of the cleaning elements while the device is being pulled through a chimney.

To set the cleaning elements 23 in proper position it is necessary to secure the pin 25 in a desired position in the slot 21 and then tighten the nut 26. The extent of the movement of the members 23 is indicated by full lines and dotted lines in Figure 5 and obviously the members may be secured in any position between their limits of movement. Thus, it will be apparent that this form of the invention may also be used in square chimneys of different width and it is preferred to use same in chimneys of uniform width throughout their length.

It is to be understood that the forms of the invention herewith shown and described are to be taken as preferred examples of the same and that various changes in the shape, size and arrangement of parts may be resorted to without departing from the spirit of the invention or the scope of the subjoined claims.

We claim:

1. A device of the character described comprising a body adapted to be reciprocated in a chimney, a cleaning element formed of two sections associated with said body and connected therewith whereby the element may be urged outwardly thereby, said connection comprising a T-shaped member rigidly secured to said body and being longitudinally slotted in its shank and in each arm, a hinge foldably connecting the sections of said cleaning element, the pivot pin of said hinge being extended whereby one end thereof is slidably secured in said slot in the shank of said T-shaped member, a nut threaded on the opposite end of said pin to secure said pin in selected positions in its slot, and guide pins carried by said cleaning elements and slidable in the slots in the arms of said T-shaped member.

2. A device of the character described comprising a substantially elliptically shaped resilient body adapted to be reciprocated in a chimney, means for varying the size of said body, cleaning elements each formed of two

sections associated with said body and connected therewith whereby the elements may be urged outwardly thereby, each connection comprising a T-shaped member rigidly secured to said body and being longitudinally slotted in its shank and in each arm, a hinge foldably connecting the sections of said cleaning element, the pivot pin of said hinge being extended whereby one end thereof is slidably secured in said slot in the shank of said T-shaped member, a nut threaded on the opposite end of said pin to secure said pin in selected positions in its slot, and guide pins carried by said cleaning elements and slidable in the slots in the arms of said T-shaped member.

In testimony whereof we affix our signatures.

ERNEST F. KAHLERT.
